UNITED STATES PATENT OFFICE.

CHARLES M. PRAUL, OF ATLANTIC CITY, NEW JERSEY, ASSIGNOR TO HENRY K. FORT, OF HADDONFIELD, NEW JERSEY

SQUARE.

No. 870,845.

Specification of Letters Patent.

Patented Nov. 12, 1907.

Application filed August 3, 1906. Serial No. 329,032.

To all whom it may concern:

Be it known that I, CHARLES M. PRAUL, a citizen of the United States, residing at Atlantic City and State of New Jersey, have invented certain new and useful 5 Improvements in a Square, of which the following is a specification.

My invention relates to improvements in squares such as used by carpenters, masons, metal workers and other mechanics, and particularly to squares having 10 the two members or blades detachable.

The object of my invention is to provide means for readily locking the blades together so that they will be held together rigidly and at right angles to each other; a further object of my invention is to form the locking 15 device for the square so that the same will be flush with the surface of the arms forming the square; a still further object of my invention is to so construct the locking device that the blades may be quickly taken apart and put together by the fingers alone without 20 the aid of other tools and so that it can be manufactured at a very low cost. My invention may also be applied to T squares.

Referring to the drawings:—Figure 1. is a plan view of the square showing my improved locking device; 25 Fig. 2. is a side view of one of the blades shown in Fig. 1. detached; Fig. 3. is a plan view of Fig. 2; Fig. 4. is a cross section on lines 4—4 Fig. 3; Fig. 5. is a plan view of the other blade shown in Fig. 1. detached; Fig. 6. is a side view of Fig. 5; Fig. 7. is a plan view of 30 a square showing a different form of locking wedge.

In the drawings A and B represent the blades of a square. When used as a T square the wider blade A will form the head of the T square and the blade B will form the long blade. The blade or head A will 35 be extended as shown in dotted lines Fig. 1. when used as a T square.

The blade B has a projecting tongue C of less thickness than the blade and has beveled edges D. The blade A has formed therein a recess E of a shape corresponding to the tongue C. The recess E is of sufficient depth to receive the tongue C and allow the surface of the same to be flush with the surface of the blade A. The recess E is provided with dove-tail edges which correspond to the beveled edges D of the tongue C. The tongue C may be made wedge shape or its sides may be parallel but I prefer to use the form shown in the drawings as it makes a tighter joint.

A key or wedge F having beveled edges is fitted into a recess G formed in the blade A. The said recess has

dove-tail edges corresponding to the edges of the key 50 F so as to hold the key from falling out of the recess G. The sides of the recess G are parallel as shown in Fig. 1. and a portion of the key F is cut on an angle to form a cam surface f. This is adapted to bear against the shoulder H on the tongue C. The shoulder H is 55 formed by cutting a recess across the face of the tongue C. When the key F is forced into the recess of the tongue C the two blades A and B will be drawn tightly together and form a very rigid joint. The blade B is provided with projecting corners I and I' which fit 60 under projecting corners J and J' on the blade A and greatly strengthen the joint as well as assuring a perfect right-angle joint.

Fig. 7. illustrates a different form of making the key F in which the same is wedge shape. A screw K enters 65 a slot L in the key to prevent the key from falling out of the recess G when the key is moved to the larger end of the said recess. In the form shown in Fig. 1. the key F can only be removed by sliding it out of the end of the recess G which can only be done after removing 70 the pin M.

By my improved form of locking device the blades are securely held together, the key will tighten the blades even after the parts have become worn and will always make a rigid right-angle joint. The blades 75 can be readily taken apart and put together without the use of tools and the parts are all flush with the surface of the blades. And the whole can be manufactured at a very low cost.

The tongue C or the key F may be made without the 80 dove-tail edges without departing from my invention but I prefer to use the form shown in the drawings as in this way the parts are more securely held together.

Having thus described my invention I claim and desire to secure by Letters Patent:—

85

1. The combination of a square having a blade, a tongue on said blade, a blade having a recess formed in the surface thereof conforming in shape with said tongue, a key, said tongue and said latter blade having formed therein a recess extending across the face of the same and adapted 90 to receive said key.

2. The combination of a square having a blade, a tongue on said blade, said tongue having its side edges beveled, a blade having a recess formed in the surface thereof having dove-tail edges to conform with said tongue, a key, said 95 tongue and said latter blade having formed therein a recess extending across the face of the same and adapted to receive said key.

3. The combination of a square having a blade, a tongue formed on the same, said tongue having a recess formed 100

- across the face of the same, a blade having a recess formed therein to receive said tongue, said latter blade having a recess formed therein having dove-tail edges, a key adapted to slide in the latter recess and lock the parts together, 5 substantially as described.
4. The combination of a square having a blade, a tongue formed on the same, said tongue having a recess formed across the face of the same, a blade having a recess formed therein to receive said tongue, said latter blade having a 10 recess formed therein having dove-tail edges, a key having

beveled edges adapted to slide in the latter recess, and said key being larger at one end than at its other end, substantially as described.

In testimony whereof I affix my signature in presence of two witnesses.

CHARLES M. PRAUL.
